UNITED STATES PATENT OFFICE.

FREDERIC CONDÉ, OF OSWEGO, NEW YORK.

GARMENT.

1,191,064.

Specification of Letters Patent. Patented July 11, 1916.

Application filed July 8, 1915. Serial No. 38,821.

To all whom it may concern:

Be it known that I, FREDERIC CONDÉ, a citizen of the United States, residing at Oswego, in the county of Oswego, State of 5 New York, have invented certain new and useful Improvements in Garments, of which the following is a description, reference being had to the accompanying drawing and to the figures of reference marked thereon.

10 My invention relates to improvements in garments, and more particularly to knitted undergarments, such as shirts, union suits, or any garments having a neck portion provided with a collaret.

15 The particular object of the present invention is to provide a novel construction of collaret.

Heretofore, it has been customary to provide undergarments with attached collar- 20 ets, and my invention is particularly an improvement thereon, whereby a unique and ornamental effect is produced.

The invention consists primarily in feeding in to the collaret strip in the process 25 of manufacture a comparatively wide stripe composed of threads of different colors and texture from the body of the collaret, the effect of which is to give a unique and ornamental appearance to the collaret. Fur- 30 thermore, the fed-in stripe furnishes a contrast in color and texture. It is also prefer- ably raised above the surface of the sur- 35 rounding portion of the collaret and is located considerably nearer the inner than the outer edge thereof.

The invention is illustrated in the accompanying drawings, in which—

Figure 1 is a plan view of a garment 40 with a collaret constructed in accordance with my invention; Fig. 2 is a view of the collaret detached; Fig. 3 is a side view of the collaret with the invention applied. Fig. 4 is a sectional view of a portion of the body of an undershirt to which my in- 45 vention has been applied; and Fig. 5 is a plan view of the collaret strip.

In these drawings, 1 represents the body of an undershirt, to which has been stitched a flat collaret 2, shown in detail in Fig. 2. 50 This flat collaret is made in a flat strip and in its formation on the knitting machine

there are fed in a number of threads preferably of silk or other material differing in texture and of much better quality and of different color from the body of the fabric. 55 These fed in threads, which may be a dozen or more in number, form a comparatively wide stripe and are so located in the body of the collaret strip that when the latter is folded around the neck portion of the 60 garment the stripe formed by these threads extends longitudinally of the strip and lies between the edge and the fold in the strip. This stripe is indicated at 3 in the drawings. The threads are preferably so fed in 65 as to form a ridge or raised portion. This raised stripe, which is formed of threads of better quality, strengthens and reinforces the collaret and serves the purpose of retaining the neck of the garment in proper shape. 70 Inasmuch as the threads forming the stripe are of different texture and may be of different coloring, there is also an ornamental effect in the finishing of the collaret upon the neck of the garment. 75

Having thus described my invention, what I claim as new and desire to secure by Letters Patent, is:

1. A garment having a folded collaret strip, said collaret strip having incorporated within it a stripe formed of threads of different character and appearance extending longitudinally of the collaret strip, located between the edge of the strip and the fold therein and serving to strengthen 85 and reinforce and ornament said collaret.

2. A garment having a folded collaret strip, said collaret strip having incorporated within it a wide stripe formed of threads of better quality extending longitudinally of the collaret strip and located between the edge of the strip and the fold therein, said stripe being raised above the adjacent surface of the collaret and serving to strengthen and reinforce said collaret. 95

In testimony whereof, I affix my signature, in the presence of two witnesses.

FREDERIC CONDÉ.

Witnesses:

M. E. CORBETT,
HARRY E. SHILL.
